(57) CLAIM

I claim the ornamental design for a bouquet container, as shown and described.

DESCRIPTION

FIG. 1 is a perspective view of a bouquet container, showing my new design;

FIG. 2 is a perspective view thereof, shown with the removable cover portion in a partially removed state;

FIG. 3 is a front elevation view thereof, shown with the removable cover portion entirely closed, as shown in FIG. 1;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines showing flower bouquets and surface indicia depict environmental subject matter only and form no part of the claimed design.
